(57) **CLAIM**

The ornamental design for a wearable device, as shown and described.

DESCRIPTION

FIG. 1 is a bottom, front, and left-side perspective view of a wearable device;

FIG. 2 is a back and left-side perspective view thereof;

FIG. 3 is a right-side elevation view thereof;

FIG. 4 is a left-side elevation view thereof;

FIG. 5 is a bottom plan view thereof;

FIG. 6 is a top plan view thereof;

FIG. 7 is a front elevation view thereof;

FIG. 8 is a back elevation view thereof;

FIG. 9 is a cross-sectional view thereof, taken along line 9-9 of FIG. 5; and,

FIG. 10 is a bottom, front, and left-side perspective view thereof, shown with a band disclosed in broken lines to illustrate an environment.

The broken lines depict portions of the wearable device in which the design is embodied that form no part of the claimed design. Additionally, the broken lines showing a band in FIG. 10 represent environment and form no part of the claimed design.

1 Claim, 10 Drawing Sheets
